(57) **CLAIM**

The ornamental design for a chuck carrier film, as shown and described.

DESCRIPTION

FIG. 1 is a top perspective view of a chuck carrier film. FIG. 2 is a bottom perspective view of the chuck carrier film. FIG. 3 is a top plan view of the chuck carrier film. FIG. 4 is a back side view of the chuck carrier film. FIG. 5 is a side view of the chuck carrier film, the opposite side view being a mirror image thereof; and, FIG. 6 is a front side view of the chuck carrier film. The broken lines in the figures form no part of the claimed design.
